BLANK FEEDING MECHANISM

Felix Hunter, Livingston, N. J., assignor to American Can Company, New York, N. Y., a corporation of New Jersey

Application September 26, 1945, Serial No. 618,736

9 Claims. (Cl. 271—4)

1

The present invention relates to a mechanism for feeding blanks and has particular reference to devices for picking up a plurality of blanks at one time and for carrying them to a place of deposit where they are collected in a stack.

An object of the invention is the provision of a blank feeding mechanism wherein a plurality of blanks arranged in a row extending longitudinally of the mechanism are picked up at one time and carried to a place of deposit where they are collected in a stack for subsequent individual feeding so that an adequate supply of blanks in the stack may be maintained in accordance with the high speed operation of machines into which the blanks subsequently are fed individually.

Another object is the provision of such a feeding mechanism wherein the operation of the mechanism is controlled by the number of blanks in the stack to insure the maintenance of an adequate supply of blanks for immediate use.

Another object is the provision of a feeding mechanism of this character wherein the blanks are picked up from a plurality of stacks by magnets arranged on an intermittently operable conveyor and are transferred to a single supply stack at a suitable place of deposit so as to maintain at the place of deposit an adequate supply of blanks for immediate use.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a blank feeding mechanism embodying the instant invention, with parts broken away; and

Fig. 2 is a side elevation of the mechanism shown in Fig. 1 with a plurality of stacks of blanks in place in the mechanism and with parts broken away and parts shown in section, the view also including a wiring diagram of the electric apparatus used in the mechanism.

As a preferred embodiment of the instant invention the drawings illustrate principal parts of a mechanism for feeding flat sheet metal can body blanks A from a plurality of stacks B of such blanks into a single stack C at a suitable place of deposit for immediate use in a subsequent operation machine. However, the mechanism is equally well adapted to articles other than sheet metal blanks and to feeding the articles from places other than stacks. For example, the blanks may be fed into the mechanism

2

direct from a slitter or other machine and may be fed immediately into the receiving stack C without the formation of the stacks B.

The blanks A preferably are arranged in the stacks B in a row. These stacks are located side-by-side and are maintained in spaced relation by a plurality of vertically disposed transverse separator plates 11 secured in a base 12 which rests on a horizontal table 13. At the bottom the stacks of blanks rest on a movable support member or platform 14. This platform when in a lowermost position rests on the base 12. The platform is formed with transverse clearance slots 16 through which the separation plates 11 extend, as best shown in Fig. 2.

The blanks A are fed from the tops of the stacks B. For this purpose the platform 14 is movable vertically, in any suitable manner and in time with the other moving parts of the mechanism, to maintain the uppermost blanks in the stacks at a constant level or plane relative to the support 13. By way of example a set of vertical feed screws 17 threadedly engaging with the platform are shown in the drawings for this purpose. They may be turned in suitable manner.

The blanks A are fed from the stacks B preferably by a pair of spaced and parallel endless chain conveyors or conveyor members 18 which have intermittent movement. These members carry a plurality of permanent magnets 19 secured to the chains at closely spaced intervals along their lengths. The conveyors extend longitudinally of the mechanism and across the top of the row of stacked blanks A, as shown in the drawings. Adjacent one end, the conveyors operate over a pair of spaced driving sprockets 21. At the opposite end of the mechanism the conveyors operate over a pair of spaced and preferably smaller diameter idler sprockets 22. A hollow rocker beam 23 extends between the sprocket 21, 22 to maintain them in a spaced relation and this beam serves as a support for the conveyors between the sprockets.

The driving sprockets 21 are mounted on a rotatable drive shaft 25 which extends through a long bearing 26 on one end of the beam 23. The ends of the shaft are carried in bearing blocks 27 formed in brackets 28 bolted on the support 13. The shaft thus forms a pivot member for the beam 23.

The idler sprockets 22 are mounted on a rotatable idler shaft 31 which is carried in a pair of spaced bearings 32 formed on this end of the beam 23. Between the bearings, the shaft car-

ries the upper end of a vertical actuating link 33. The lower end of the link connects with a crank 34 which is mounted on a shaft 35 carried in a pair of spaced bearings 36 bolted to the support 13. The shaft 35 is rotated in any suitable manner in time with the other moving parts of the mechanism.

Rotation of the shaft 35 rotates the crank 34 and thus moves the link 33 vertically. This vertical movement of the link rocks the beam 23 on its pivot or drive shaft 25 through a down stroke and thence through an up or return stroke. On the down stroke of the beam, the magnets 19 on the conveyors 18 come into engagement with the uppermost blanks A in the several stacks B, as shown by the dot and dash lines in Fig. 2. This attracts and picks up these blanks. On the up stroke of the beam, the picked-up blanks are carried upward away from and clear of the stacks B. This picking up of the blanks from the stacks takes place while the conveyors remain stationary, that is while they are on the stop phase of their cycle.

When the picked-up blanks A are entirely clear of the stacks B, the conveyors 18 again move and this advances all of the picked-up blanks toward the driving sprockets 21. The driving sprockets 21 are intermittently rotated in time with the vertical rocking movement of the beam 23 by a helical gear 38 and a meshing interrupted helical gear 39. Thus the beam is moving up and down while the conveyor chains are advancing, the chains being at rest while the crank 34 is passing over its dead center at the bottom of the stroke.

The gear 38 is mounted on one end of the drive shaft 25. The interrupted gear 39 is mounted on the upper end of a vertically disposed gear drive shaft 41 which is carried in suitable bearings and which is rotated in any suitable manner in time with the other moving parts of the mechanism.

During the rotation of the drive sprockets 21 and the resulting travel of the conveyors 18, the picked-up blanks A held by the magnets 19 are carried to a position directly over a magazine 43 disposed under the drive sprockets 21. At this place they are stripped off or removed from the magnets whereupon they fall into the magazine as the magnets pass over the magazine.

This stripping action is effected by a stripper plate 44 which is located between the drive sprockets 21 and in the path of travel of the blanks clinging to the magnets. The stripper plate is bolted to the magazine. The magazine may form a part of a subsequent operation machine. The magazine may be bolted to a frame 45 which may be the main frame of such a machine.

When all of the blanks A are stripped off from the magnets 19 and into the magazine 43 during this step advancement the stack C is thus built up by that number of blanks. At the beginning of the rest period of the conveyors 18, the beam 23 has reached its lowered position to pick up another row of blanks from the tops of the row of stacks B for transfer and deposit into the magazine to augment the stack C. In this manner repeated rocking movement of the beam 23 together with the intermittent movement of the conveyors 18 result in a high speed feeding of the blanks A from the several stacks B into the single stack C.

In this manner there is maintained in the magazine 43 an adequate supply of blanks. Such a feeding device, therefore, is well adapted for the 75

continued operation of subsequent operation machines. During this feeding of the blanks, the uppermost blanks in the several stacks B preferably are maintained in the same horizontal level by vertical lifting of the platform 14. Such elevating of the stacks is in time with the rocking of the beam 23, as hereinbefore mentioned.

Provision is made for controlling the operation of the mechanism in accordance with the supply of blanks in the stack C in the magazine 43. This control is exercised preferably through a plurality of electric circuits which govern the operation of an electric motor 51, indicated in the wiring diagram of Fig. 2, which constitutes the main source of power for rotating the shafts 35 and 41 of the mechanism.

Making and breaking of these circuits is brought about by opening and closing a pair of electric toggle switches. One of the pair is a low stack switch 52, the other is a high stack switch 53. Both switches may be secured to the outside of the magazine 43. These switches are opened and closed by respective pivotally mounted switch arms 54, 55 which are maintained under spring pressure and which extend into the magazine through slots 56 formed in the side thereof. These switches normally close their respective circuits unless operated on.

When blanks A in the stack C in the magazine 30 43 engage against the switch arms 54, 55 the arms are forced outwardly. This opens the switches. When the magazine is filled to capacity with the blanks, both switches 52, 53 are held open and the feeding mechanism does not operate and 35 no feeding of blanks from the stacks B takes place.

As the blanks in the stack C are discharged from the magazine 43 as when used in a subsequent operation machine, the top of the stack 40 of blanks drops below the high stack switch arm 55. This arm thereupon moves inwardly under the action of a spring 58. This closes the high stack switch 53 but the closing of this switch alone is not sufficient to set the feeding mechanism 45 into operation. When the top of the stack of blanks in the stack C is below the low stack switch arm 54, the spring designated by the numeral 59 forces the arm inwardly and this closes the low stack switch 52.

The closing of the low stack switch establishes a stacking circuit X which includes a solenoid 61 of a normally open relay switch 62. This circuit as well as others to be hereinafter described, transmits electric energy from a main circuit Y having a main lead wire 63 and a return wire 64 connecting with a suitable source of electric energy such as a generator 65. The electric motor 61 is also connected to these lead and return wires 63, 64, the return wire including a normally open motor relay switch 66 disposed adjacent the motor and actuated by a solenoid 67.

Hence with the closing of the low stack switch 52 electric energy from the main lead wire 63 flows along a wire 71, solenoid 61, a wire 72, through the low stack switch 52, and along a wire 73 to the return wire 64. Energy flowing along this circuit energizes the solenoid 61 and closes the normally open relay switch 62. Closing of the relay switch establishes a holding circuit W which cuts out the low stack switch 52 and thus permits continued operation of the feeding mechanism as the blanks A newly deposited in the magazine 43 build up the stack C above the low stack switch arm 54.

With the closing of the relay switch 62, elec-

tric energy from the main lead wire 63, passes along wire 71, solenoid 61, wire 72, a connecting wire 74, switch 62, a wire 75, the closed high stack switch 53, a wire 76, solenoid 67 of motor switch 66, and a wire 77 to the return wire 64. Energy passing along this holding circuit energizes the motor solenoid 67 and thus closes the motor switch 66. Closing of this motor switch completes the generator circuit Y leading to the motor 51 and thus operates the motor for a 10 period as long as the motor switch 66 remains closed.

With the continued operation of the motor 51, the blanks A deposited into the magazine build up the stack C until the stack becomes so high that the blanks press the high stack arm 55 outwardly a distance sufficient to open the high stack switch 53. The opening of this switch breaks the holding circuit W and hence deenergizes the motor solenoid 67. This permits the motor switch 66 to open and this breaks the generator circuit Y.

Hence the motor stops operating and the feed mechanism ceases feeding of the blanks A from the stacks B into the single stack C in the magazine 43. The mechanism remains in this stopped condition until the stack C again runs low at which time the establishment of the above described circuits is repeated to again build up the stack C. It is in this manner that the mechanism is controlled by the condition of the stack C, as hereinbefore mentioned.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a mechanism for feeding blanks, the combination of a conveyor, a support disposed adjacent said conveyor for supporting a plurality of blanks arranged in a row extending longitudinally of said conveyor, means for moving said conveyor toward and away from the blanks on said support, means on said conveyor for picking up the blanks on said support when the conveyor is moved into a position adjacent said blanks, means for actuating said conveyor to carry the picked-up blanks to a place of deposit, stripper means at said place of deposit for stripping the picked-up blanks from said conveyor, and electrical means having a high stack switch and a low stack switch engageable with the deposited blanks for controlling the actuation of said conveyor to insure a maximum and a minimum of deposited blanks.

2. In a mechanism for feeding blanks, the combination of an endless conveyor, a support disposed below said conveyor for supporting a plurality of blanks arranged in a row extending longitudinally of said conveyor, means for moving said conveyor toward and away from the blanks on said support, means on said conveyor for picking up the blanks on said support when the conveyor is moved into a position adjacent said blanks, means for actuating said conveyor to carry the picked-up blanks to a place of deposit, a magazine at said place of deposit, and means adjacent said magazine for removing the picked-up blanks from said conveyor for deposit in said magazine in an orderly stacked arrangement.

3. In a mechanism for feeding blanks, the combination of an endless conveyor, a support disposed below said conveyor for supporting a plurality of blanks arranged in a row extending longitudinally of said conveyor, means for moving said conveyor toward and away from the blanks on said support, means on said conveyor for picking up the blanks on said support when the conveyor is moved into a position adjacent said blanks, means for actuating said conveyor to carry the picked-up blanks to a place of deposit, means at said place of deposit for removing the picked-up blanks from said conveyor for deposit in an orderly stacked arrangement, and means at said place of deposit and engageable with the deposited blanks for controlling the actuation of said conveyor.

4. In a mechanism for feeding blanks, the combination of an endless conveyor, a support disposed below said conveyor for supporting a plurality of rows of blanks arranged side by side longitudinally of said conveyor, a pivotal mounting for one end of said conveyor, means adjacent the opposite end of said conveyor for moving said conveyor toward and away from the blanks on said support, a plurality of pick-up devices carried by said conveyor for picking up the uppermost blank in each row of blanks on said support when the conveyor is moved into a position adjacent said blanks, means for actuating said conveyor to carry the picked-up blanks to a place of deposit, and stripper means at said place of deposit for successively removing the picked-up blanks from said conveyor and for collecting them in a single stack.

5. In a mechanism for feeding blanks, the combination of an endless conveyor, a support disposed below said conveyor for supporting a plurality of stacks of blanks arranged in a row extending longitudinally of said conveyor, means for moving said conveyor toward said stacks of blanks, means on said conveyor for picking up the top blanks from the stacks of blanks when the conveyor is so moved, means for actuating said conveyor to carry the picked-up blanks longitudinally of the row of stacks of blanks and to a place of deposit, and means at said place of deposit for removing said blanks from the conveyor and for collecting them in a single stack.

6. In a mechanism for feeding blanks, the combination of an endless conveyor, a support disposed below said conveyor for supporting a plurality of stacks of blanks arranged in a row extending longitudinally of said conveyor, means for moving said conveyor toward said stacks of blanks, magnetic means on said conveyor for picking up the top blanks from the stacks of blanks when the conveyor is so moved, means for intermittently actuating said conveyor to carry the picked-up blanks longitudinally of the row of stacks of blanks and to a place of deposit, and means at said place of deposit for removing said blanks from the conveyor during the intermittent actuation of the conveyor and for collecting them in a single stack.

7. In a mechanism for feeding blanks, the combination of an endless conveyor, a support having a movable platform disposed below said conveyor for supporting a plurality of stacks of blanks arranged in a row extending longitudinally of said conveyor, separator plates secured in said support and extending up through openings in said platform for maintaining the stacks of blanks in separated positions, means for moving said conveyor toward said stacks of blanks,

means on said conveyor for picking up the top blanks from the stacks of blanks when the conveyor is so moved, means for actuating said conveyor to carry the picked-up blanks longitudinally of the row of stacks of blanks and to a place of deposit, and means at said place of deposit for removing said blanks from the conveyor and for collecting them in a single stack.

8. In a mechanism for feeding blanks, the combination of an endless conveyor, a support disposed below said conveyor for supporting a plurality of stacks of blanks arranged in a row extending longitudinally of said conveyor, means for moving said conveyor toward and away from the blanks on said support, means on said conveyor for picking up the top blanks from the stacks of blanks on said support when the conveyor is moved into a position adjacent said blanks, devices for shifting said support to keep the top of the stacks at a predetermined level to facilitate removal of the top blanks therefrom by said conveyor, means for actuating said conveyor to carry the picked-up blanks to a place of deposit, and means at said place of deposit for removing the picked-up blanks from said conveyor.

9. In a mechanism for feeding blanks, the combination of an endless conveyor, a support dis-

posed below said conveyor for supporting a plurality of stacks of blanks arranged in a row extending longitudinally of said conveyor, means for moving said conveyor toward and away from the blanks on said support, means on said conveyor for picking up the top blanks from the stack of blanks on said support when the conveyor is moved into a position adjacent said blanks, devices for lifting said support in synchronism with the movement of said conveyor to keep the top of the stacks at a predetermined level to facilitate removal of the top blanks therefrom by said conveyor, means for actuating said conveyor to carry the picked-up blanks to a place of deposit, and means at said place of deposit for removing the picked-up blanks from said conveyor.

FELIX HUNTAR.
